[57] CLAIM

The ornamental design for a sphygmomanometer sensor and cuff coupling mechanism, as shown.

DESCRIPTION

FIG. 1 is a front perspective view of a sphygmomanometer sensor and cuff coupling mechanism showing my new design;

FIG. 2 is a rear elevational view thereof;

FIG. 3 is a right end elevational view thereof;

FIG. 4 is a left end elevational view thereof; and

FIG. 5 is a bottom plan view thereof.
